UNITED STATES PATENT OFFICE

2,517,305

SPLASH GUARD FOR SHOES

Basil A. Guggisberg and John S. Kuslich,
St. Paul, Minn.

Application April 20, 1948, Serial No. 22,098

2 Claims. (Cl. 36—70)

1

This invention relates to improvements in devices to prevent the splashing of mud, water and debris from the heel of a shoe upon a wearer's apparel.

It is a well known fact that as an incident of walking in wet and muddy weather lifting of the heel will cause water to splash upwardly upon the stockings of the wearer and sometimes mud and grains of dirt and sand will also be thrown upwards entering the shoe or contacting the stockings, trousers and other wearing apparel and also entering the seams of the shoe adjacent to the heel. It is the purpose of this invention to provide a relatively cheap splash guard for attachment to the heel of the shoe, having improved means to facilitate accurate position application upon the heel; the device embodying improved means to cause the water splashed under the guard to drain forwardly and not to the outer edge of the guard.

Other objects and advantages of the invention will be apparent from the following detailed description.

In the accompanying drawing, forming a part of this specification, and wherein similar reference characters designate corresponding parts throughout the several views:

Figure 1 is a side elevation of a shoe showing the guard mounted upon the heel.

Figure 2 is a perspective view of the improved splash guard.

Figure 3 is a cross sectional view taken substantially on the line 3—3 thru the heel of the shoe shown in Figure 1 and showing more particularly the application of the guard.

Figure 4 is a vertical cross sectional view taken substantially on the line 4—4 of Figure 3.

Figure 5 is a modified form of the guard; the same showing a vertical cross sectional view similar to Figure 4.

In the drawing, wherein for the purpose of illustration are shown preferred and modified forms of the invention, the letter A may generally designate the form of invention shown in Figures 1 to 4 inclusive and B the form of invention shown in Figure 5. Insofar as the two forms of invention A and B employ similar structure, the same reference characters have been applied to the drawing.

The improved shoe guard preferably comprises a shield or guard body 10 which may be formed of sheet-like plastic or metal. Preferably, plastic is used, either transparent or colored to suit. The body 10 has a curvature, preferably of greater than 180°, as shown in Figure 3, so as to cover the rear and side surfaces of the heel 11. The

body 10 slopes outwardly and downwardly from the upper edge 12 to the lower edge 13a. The degree of slope must be sufficient to provide for proper splash protection; being in the neighborhood of 45°. The forward corner marginal edges 12a and 12b are rounded to prevent damage of the shoe heel surfaces, and the lower front edges may also be rounded. The ends of the C-shaped body 10 are provided with retaining straps 13 which secure the ends of the elastic clamping band 14 to the body 10. These straps 13 in the event the body is made of plastic may be integral with the body or secured thereto by means of some plastic solvent or adhesive. The band 14 is normally under slight tension to draw the two ends of the body 10 together. Intermediate its ends the band 14 is provided with a forwardly extending finger grasping projection 15, provided by doubling the material of the band together and stitching it at 16.

Upon the under sloping surface of the body 10, between the ends of the body 10 there is provided a shape retaining and position holding member 20, which may be a block of plastic molded integral with the body or secured thereto by some suitable plastic adhesive or solvent. The member 20, shown in Figure 4, has a forward surface normally vertically positioned when the guard is applied upon the heel. This surface is serrated, as shown at 21 in Figure 4 so that the guard will not slip downwardly upon the heel. Of course the member 20 prevents the elastic from deforming the shape of the guard at the rear of the heel, as is quite evident.

Referring to the form B, the under side of the guard body at the rear may be provided with a projection 20a similar to projection 20 above described, but having forwardly thereon a pliable suction cup 25, of rubber or synthetic material, adapted to engage and adhere to the rear of the heel 11 in a manner and for a purpose well understood. The projection or member 20a is, of course, spaced inwardly from a vertical plane contacting the rear of the edge 12 of the guard, in contradistinction to the shape of the member 20 for the form of invention A above described.

Another and improved feature of the invention is the provision of a beaded or ribbed lower margin 30 for the guard body 10 projecting inwardly from the inner surface of the guard body and providing a drip surface 31 which slopes forwardly from the inner surface of the body 10 and terminates in a drip edge 32 sufficiently spaced as to prevent the water being thrown over the top of the guard as an incident of walking.

The shields or guards may be made in pairs,

that is, rights and lefts if found necessary, and of course the splash guards may be made in different sizes.

Various changes in the shape, size and arrangement of parts may be made to the forms of the invention herein shown and described without departing from the spirit of the invention or the scope of the following claims.

We claim:

1. As an article of manufacture a splash guard for application to the heels of shoes comprising a substantially C-shaped body of sheet-like material which is of a nature to hold its shape but may flex at the ends thereof to increase or decrease the size of the opening in the C-shaped body, an elastic band secured at its ends to the ends of the C-shaped body normally under tension to draw said ends together and restrict the opening, said elastic band having a forwardly extending finger projection, said C-shaped body upon the under surface thereof intermediate its ends having a narrow forwardly extending rigid shape and position retaining projection of a nature to engage the heel of the shoe to prevent sliding of the body along the heel, and a drip bead at the lower margin of the body faced inwardly forwardly beyond the inner surface of the body to permit drip of water, etc. from the under surface of the body downwardly and inwardly thereover.

2. As an article of manufacture a splash guard for application upon the heels of shoes comprising a substantially C-shaped body of sheet-like plastic material of a nature to hold its shape but capable of flexing at its ends to increase or decrease the size of the opening thereto, an elastic band secured at its ends to the ends of the C-shaped body normally under tension to draw said ends together and restrict the opening, said C-shaped body being of substantially uniform

thickness and having an under surface which normally slopes downwardly and outwardly when upon a heel of a shoe and upon said surface midway between the ends of the body having a narrow projection with a forwardly facing anti-slip surface, said projection terminating at its lower end below the lower margin of the body, the lower margin of said body being provided with an integral splash deflecting rib providing an inner unchannelled surface which merges into the inner surface of the body and projects forwardly and inwardly of the inner surface of the body to drain water from the inner surface of the body directly downwardly thereover and directly off the bead, said bead extending continuously around said margin of the body and also being located beneath said projection.

BASIL A. GUGGISBERG.
